BRIDGE FOR GUITARS

Grover G. Fields, Stanton, Calif., assignor to Columbia
Broadcasting System, Inc., New York, N.Y., a corpora-
tion of New York

Filed Dec. 29, 1967, Ser. No. 9,990

Term of patent 14 years

Int. Cl. D17—03

U.S. Cl. D56—1

FIG. 1.

FIG. 6.

FIG. 2.

FIG. 3.

FIG. 4.

FIG. 5.

FIGURE 1 is a perspective view of a bridge for guitars, embodying my new design;

FIGURE 2 is a top plan view thereof;

FIGURE 3 is a side elevational view of the bridge, showing the side not shown in FIGURE 1;

FIGURE 4 is an end elevational view of one end of the bridge;

FIGURE 5 is an end elevational view of the other end thereof, and

FIGURE 6 is a bottom plan view of the bridge.

The dominant features of the design reside in the portions shown in solid lines.

I claim:

The ornamental design for a bridge for guitars, substantially as shown and described.
